INVENTOR:
PAUL O. CARTUN,

BY
Theodore S. Hunt.

HIS ATTORNEY.

UNITED STATES PATENT OFFICE.

PAUL O. CARTUN, OF CLEVELAND HEIGHTS, OHIO, ASSIGNOR TO GENERAL ELECTRIC COMPANY, A CORPORATION OF NEW YORK

ELECTRIC INCANDESCENT LAMP.

Application filed June 9, 1925. Serial No. 36,054.

My invention relates to electric incandescent lamps, and more particularly to improvements in the mounting and arrangements of the filaments therein.

5 The advantages of using in vacuum lamps closely coiled metal filaments of the type used in the gas-filled lamps disclosed in Langmuir Patent No. 1,180,159, issued April 18, 1916, have been recognized. However, 10 the vacuum lamp requires a less concentrated filament than the gas-filled lamp and difficulty has been experienced in supporting such a filament without using a comparatively large number of support wires and 15 this resulted in comparatively high cooling of the filament and consequent lowering of efficiency. The object of my invention is to provide a filament and mounting therefor so disposed as to give a desirable light 20 distribution with a comparatively low cooling effect from filament supports and hence a comparatively high efficiency. Further advantages and features of my invention 25 will appear from the following description of species thereof. While my invention is of particular advantage in vacuum lamps, it is not restricted thereto and may be used to advantage in gas-filled lamps.

The invention is illustrated in the accompanying drawing, in which Fig. 1 is a front elevation of an electric incandescent lamp comprising my invention; Fig. 2 is a fragmentary side elevation thereof; Fig. 3 is a sectional plan view along the lines 3—3 35 of Fig. 1; Fig. 4 is a front elevation of an electric incandescent lamp comprising a modification of my invention; Fig. 5 is a fragmentary side elevation thereof; and Fig. 6 is a perspective of an electric incandescent lamp comprising still another modification of my invention.

Like parts are designated by the same characters of reference in all the various figures.

45 Referring to the drawings, 10 is a bulb of an electric incandescent lamp having a base 11 at its outer end and a stem 12. Into the latter are sealed the leading-in wires 13—14 which are connected to the conductors 15—16

usually of copper or nickel. A comparatively short longitudinally extending rod 17 of glass or other insulating material is united to the stem 12 and has formed on its inner end a button 18 which has embedded therein the wires 19, 20 and 21 ordinarily of metal such as tungsten or molybdenum. The supports 19 and 20 extend longitudinally of the lamp, and more specifically, are located in a plane which includes the longitudinal axis of the lamp. 50 The support 21 extends transversely of the lamp and, more specifically, lies in a plane normal to the longitudinal axis of the lamp. The supports 19, 20 and 21 with the help of the conductors 15—16 resiliently support the filament 22. The said filament is of the closely coiled form, preferably tungsten. The filament passes through loops at the ends of the supports and is free to slide therein when the lamp is subjected to shock 55 and to compensate for expansion or contraction arising from temperature changes.

The lamp shown in Fig. 4 differs from that shown in Fig. 1 in that there is more horizontal disposition of the filament. In 75 the lamp shown in Fig. 6, the filament has an intermediate position. Further variations may be made in the disposition of the filament according to the general direction of distribution desired.

80 What I claim as new and desire to secure by Letters Patent of the United States, is:—

In an electric incandescent lamp, the combination of a support comprising a seal portion and an insulating rod extending therefrom substantially axially of said lamp, leading-in wires having ends spaced transversely from the end of said rod, a pair of support wires extending approximately longitudinally of the lamp from the end of 85 said rod, a third support wire extending transversely of said lamp from the end of said rod, and a filament supported solely upon the ends of the said leading-in wires and support wires.

95 In witness whereof, I have hereunto set my hand this 6th day of June, 1925.

PAUL O. CARTUN.
